UNITED STATES PATENT OFFICE.

JAY COOK, OF COLDWATER, MICHIGAN.

SIGNAL.

Application filed June 8, 1923. Serial No. 644,194.

To all whom it may concern:

Be it known that I, JAY COOK, a citizen of the United States, residing at Coldwater, in the county of Branch and State of Michigan, have invented a new and useful Signal, of which the following is a specification.

This invention aims to provide a simple means whereby a signal may be displayed at a railroad crossing, when a train is approaching the crossing.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed it being understood that, within the scope of what is claimed, changes in the precise embodiment of the invention shown can be made without departing from the spirit of the invention.

In the accompanying drawings:—

Figure 1 shows in top plan, a device constructed in accordance with the invention; Figure 2 is a side elevation wherein parts are removed; Figure 3 is a section on the line 3—3 of Figure 1; Figure 4 is a section on the line 4—4 of Figure 2; Figure 5 is a section on the line 5—5 of Figure 1.

In the drawings, there is shown a railroad track comprising, at one side, a rail 1, and comprising, at its opposite side, rails 2 and 3, the numeral 4 denoting a highway crossing. The purpose of the invention is to provide a means for displaying a signal at the crossing 4 when a train approaches the crossing on the track.

The ends of the rails 2 and 3 are spaced apart to form a recess 5. The spaced ends of the rails 2 and 3 are united by an outer fish plate 6 and an inner fish plate 7, the fish plates being held to the ends of the rails 2 and 3 by securing elements 8. A base flange 9 of the inner fish plate 7, which rests on certain of the ties 10, is provided with depending projections 11 (Figure 5) engaging the inner edges of the said ties, the projections being spaced apart. The upper surfaces of the projections 11 slant downwardly and inwardly to form a seat or recess 12. Disposed below one of the ties 10 is a casing 14 having an inwardly extended horizontal guide 15 (Figure 2). A plunger 16 is

mounted for reciprocation in the guide 15, in the upper portion of the casing 14, and in the inner fish plate 7, between the projections 11, as shown best in Figure 5. The plunger 16 is supplied at its upper end with a head 17, the upper surface of which may be convexed as indicated at 18, the head 17 being located close to the spaced ends of the rails 2 and 3, as shown in Figure 1. The head 17 is equipped with a lateral lug 19 mounted to slide in the recess 5 which exists between the ends of the rails 2 and 3. A compression spring 20 is interposed between the lower end of the plunger 16 and the bottom of the casing 14.

A bell crank lever 21 is located in the casing 14 and is fulcrumed at 22 on bearings 23 carried by the casing 14. The bell crank lever 21 comprises a short lateral arm, received in a slot 24 formed in the plunger 16, the bell crank lever comprising a longer up-standing arm which is pivoted at 25 to an operating member or rod 26, slidably received in a tubular shield 27, one end of the shield being connected to the casing 14 and the other end of the shield being connected to the enlarged base 28 of an upright tubular standard 29, the upper portion of the base 28 being provided with a hinged lid 30 giving access to the working parts within the base 28. Connections 31 are interposed in the tubular shield 27 and extend upwardly above the surface of the ground, screw plugs 32 or other closures being mounted in the connections 31. When the plugs 32 are removed, a lubricant may be inserted into the tubular shield 27. It will be understood that the tubular shield 27 and the operating member or rod 26 may be of any desired length, so that the casing 14 may be located at considerable distance from the standard 29, thereby to afford an adequate period of time between the actuation of the signal mechanism, hereinafter described, and the arrival of the train at the highway crossing 4.

The operating member or rod 26 extends within the base 28 of the standard 29 and is pivoted at 33 to an arm 34 on a horizontal shaft 35 (Figure 3) journaled in bearings 36 located on opposite side walls of the base 28. The shaft 35 is supplied with an arm 37, disposed at an angle to the arm 34, the arm 37 being pivoted at 39 to a pitman 38 which extends upwardly through the standard 29.

At its upper end, the standard 29 is pro-

vided with a transverse head 40 which is open at the bottom, the head being provided at one end with an enlargement 41. A lever 42 is located in the head 40 and is fulcrumed intermediate its ends, as at 43, on the standard 29. One end of the lever 42 projects beyond the head 40 as shown in Figure 2 and carries a counter-weight 44, adjustably held in place by a set screw 45 or the like. 10 The upper end of the pitman 38 is pivoted to the lever 42, as indicated at 46. The lever 42 carries a plate 47 housed within the enlargement 41 of the transverse head 40 and carrying a suitable monitory legend 15 as clearly shown in Figure 2. A spring arm 48 is connected at one end to the head 40 and is adapted to engage the lever 42, when that end of the lever which carries the plate 47 swings upwardly, the spring arm 48 being a cushioning spring, the function of which will be understood clearly 20 when Figure 2 of the drawings is examined.

In practical operation, when the wheel of a locomotive engine or other piece of rolling stock moves along the rails 2 and 3, the flange of the wheel may engage the convexed surface 18 of the head 17 of the plunger 16, or the body portion of the wheel may engage the lug 19 on the head 17. In any event, the plunger 16 will be forced downwardly, the spring 20 being compressed. When the plunger 16 moves downwardly, the bell crank 21 will be tilted on its fulcrum 22 and motion will be imparted to the operating member or rod 26, the shaft 35 being rotated by way of the arm 34, and the arm 37 imparting movement to the pitman 38, the pitman moving downwardly in the standard 29 and tilting the lever 42 on its fulcrum 43, the plate 47 being exposed with respect to the enlargement 41 of the arm 37 on the standard 29, notice thus being given to the drivers of vehicles moving along the highway toward the crossing 4, that a train is approaching the crossing on the track 1-2-3.

After the wheels of the train have passed off the head 17 of the plunger 16, the plunger 16 moves upwardly, responsive to the action of the spring 20, the parts being restored to the positions of Figure 2 by the action of the spring 20, assisted by the action of the adjustable weight 44 on the lever 42, one arm of the bell crank lever 21 also assisting in restoring the parts to the positions shown in Figure 2. The head preferably is bolted to the plunger, and is so constructed, as shown in Figure 17, that it will aid in freeing the ice from the rail, should ice accumulate on the rail. It will be obvious that the structure shown in this application may be made in double form, so as to provide for a signal regardless of which

way the train is moving on the track, this detail being a mere duplication, well understood by those skilled in the art and requiring no specific delineation.

What is claimed is:—

1. In a device of the class described, a track rail, a casing and a standard spaced longitudinally of the rail, a tubular shield extended between the casing and the standard, a plunger slideable in the casing and comprising a head disposed adjacent to the rail for engagement by a wheel moving along the rail, an operating member slideable in the shield, a bell crank lever fulcrumed on the casing and forming a connection between the operating member and the plunger, a shaft mounted to rock in the standard, a pitman movable longitudinally in the standard, arms carried by the shaft and connected, respectively with the pitman and with the operating member, and a signal arm fulcrumed on the standard, the pitman being connected with the signal arm. 70 75 80 85

2. In a device of the class described, a track rail, a hollow standard located adjacent to the track rail, a shaft mounted to rock in the standard, a pitman mounted for reciprocation in the standard, arms carried by the shaft, one arm being connected to the pitman, means assembled with the other arm for rocking the shaft from a remote point along the rail, a transverse arm carried by the standard, a signal lever fulcrumed intermediate its ends on the standard and operating in the arm, the upper end of the pitman being pivoted to the lever, a spring carried by the arm and resisting the upward swinging movement of one end of the lever, a signal carried by said end of the lever, a weight adjustable along the other end of the lever, and means for holding the weight in adjusted positions on the lever. 90 95 100 105

3. In a device of the class described, a pair of rails spaced apart longitudinally to form a recess, a fish plate connecting the rails, a plunger mounted to slide in the fish plate and including a head provided with a projection movable in the recess, a casing wherein the plunger is slidably received, spring means for elevating the plunger, a signal located remotely with respect to the casing, actuating means for the signal, comprising spaced members, one of which is located in the casing, and a connection between said members. 110 115

In testimony that I claim the foregoing 120
as my own, I have hereto affixed my signature
in the presence of two witnesses.

JAY COOK.
